UNITED STATES PATENT OFFICE

133,944

DESIGN FOR A GRAVE MARKER

Gilford Duff Adams, Butterfield, Mo.

Application July 29, 1942, Serial No. 107,735

Term of patent 14 years

To all whom it may concern:

Be it known that I, Gilford Duff Adams, a citizen of the United States, residing at Butterfield, in the county of Barry and State of Missouri, have invented a new, original and ornamental Design for a Grave Marker, of which the following is a specification, reference being had to the accompanying drawing, forming part thereof.

Figure 1 is a front elevational view of a grave marker showing my new design.

Figure 2 is a side elevational view.

Figure 3 is a sectional view taken substantially on line 3—3 of Figure 1, and

Figure 4 is a top plan view showing the grave marker in a horizontal position without the base.

I claim:

The ornamental design for a grave marker, as shown.

GILFORD DUFF ADAMS.
